INFANT FEEDING SPOON

Jean de Hymel, Pasadena, Calif.

Application August 4, 1952, Serial No. 20,893

Term of patent 14 years

(Cl. D44—29)

To all whom it may concern:

Be it known that I, Jean de Hymel, a citizen of the United States, residing at Pasadena, county of Los Angeles, State of California, have invented a new, original, and ornamental Design for an Infant Feeding Spoon, of which the following is a specification, reference being had to the accompanying drawing, forming part thereof, in which:

Fig. 1 is an isometric view of an infant feeding spoon showing my new design;

Fig. 2 is a side elevational view; and

Fig. 3 is a top plan view thereof.

I claim:

The ornamental design for an infant feeding spoon, substantially as shown.

JEAN DE HYMEL.
